United States Patent Office

Des. 197,689
Patented Mar. 10, 1964

197,689

CIGARETTE HOLDER

Monte L. Levin, Roslyn Heights, N.Y., assignor to
S. Lawrence Atkins, Jamaica, N.Y.

Filed Aug. 5, 1963, Ser. No. 76,113

Term of patent 14 years

(Cl. D85—8)

FIG. 1 is a perspective view of a cigarette holder showing my new design;

FIG. 2 is a side elevational view on an enlarged scale;

FIG. 3 is a top plan view thereof, the bottom being the same in appearance as the top;

FIG. 4 is an end view thereof looking into the mouthpiece; and

FIG. 5 is an end view thereof looking into the cigarette receiving socket of the cigarette holder.

I claim:

The ornamental design for a cigarette holder, as shown and described.
